TRAP

Charles L. Myerly, Lewistown, Pa.

Application July 17, 1935, Serial No. 31,901

1 Claim. (Cl. 137—103)

This invention discloses a trap for water of condensation or the like, characterized by a novel, float operated valve construction, by a novel, built-in sediment chamber, and by other advantages incident to the details of structure herein-after described. A mechanic who works within the scope of what is claimed need not adhere to the precise structure described and depicted.

Fig. 1 is a vertical section of the trap, and Fig. 2 is a plan of the receptacle, minus the lid.

For convenience in describing the relative location of parts, the forward end of the trap is marked by the letter A and the rear end by the letter B.

There is provided a receptacle 1 including a body 2 having a narrowed rear extension 3, the bottom of which is higher than the bottom of the body proper. A lid 4 is detachably secured at 5 to the body 2 and has an upward bulge 6, carrying a petcock 7, under the control of an operator, and used to vent the receptacle of air, upon occasion. The lid 4 has a depending lug 8, located in the extension 3 of the body 2. The bottom of the extension 3 is provided with a bore 9 into which an outlet pipe 10 is threaded. A valve support 11 is threaded into the bottom of the extension 3 and has a duct 12 communicating with the bore 9. There is a curved seat 14 in the upper end of the support 11. A valve 15 is provided and has a curved lower end 16, convexed to fit fluid-tight in the concaved seat 14 of the support 11. The valve 15 is kept in place by gravity. The valve 15 has an angular passage 17, the forward end of which communicates with the receptacle 1, by way of the extension 3 of the body 2. The lower end of the passage 17 is adapted to be closed by the seat 14 of the support 11 when the valve 15 is in the vertical position of Fig. 1. The upper end 18 of the valve 15 is tapered, and is located directly beneath the lug 8 on the lid 4. The space between the upper end of the valve 15 and the lug 8 is less than the depth of the seat 14 in the support 11, and the valve 15, therefore, cannot become detached from the support 11. The rear side of the valve 15 is cut away at 19, so that the valve can tilt enough to bring the lower end of the valve passage 17 into registration with the duct 12 of the valve support 11.

The means for operating the valve 15 embodies an arm 20 secured to the valve and carrying a float 21 located in the receptacle 1.

An inner baffle 22 is interposed between the float 21 and the inlet pipe 26 for the receptacle 1, the inlet pipe being mounted in a bore 25

formed in the body 2. The inner baffle 22 is connected to the bottom of the body 2 and to the sides thereof. An outer baffle 23 is disposed in front of the inner baffle 22, the outer baffle extending upwardly into contact with the lid 4, the vertical edges of the outer baffle being connected to the sides of the body 2. The baffle 22 and the adjacent portions of the body 2 of the receptacle form a sediment chamber 27. A plug 24, threaded into the body 2, or some equivalent for the plug, constitutes means under the control of an operator for draining sediment out of the chamber 27.

The water enters the receptacle 1 by way of the pipe 26 and the bore 25. The water is directed downwardly into the sediment chamber 27, by the baffle 23, and upwardly into the float chamber receptacle, by the baffle 22. The sediment can be drawn off at any time by removing the part 24.

The water enters the float chamber of the receptacle 1, raises the float 21, and tilts the valve 15, by way of the arm 20, until the lower end of the passage 17 in the valve 15 registers with the duct 12 of the valve support 11. This permits the water to run off through the pipe 10. When enough water has been drained off, the parts resume, approximately, the positions indicated in Fig. 1, the valve passage 17 being closed. The elongated form of the valve 15 enables the passage 17 to rock out of register with the duct 12 by a motion at right angles to that imparted by the float 21.

The device, among other features, is characterized by a novel, built-in dirt catcher, by a novel, float operated valve, which is self-grinding, and by novel means for keeping the valve in place, it being possible to remove the valve and its float by taking off the lid 4, the lug 8 on the lid then being removed from its position above the valve.

What is claimed is:

In a device of the class described, a receptacle having an inlet, a valve support mounted on the bottom of the receptacle and provided in its upper end with a concaved seat, the receptacle being provided with an outlet including a duct in the valve support, the duct leading to the seat, a vertically-elongated valve of greater height than diameter, having a convexed lower end shaped to fit closely upon the seat and mounted to rock therein, the valve having an angular bore-like passage, adapted to be closed by the seat but registering with the duct when the valve is rocked to a given position, the intake end of the passage being spaced from the seat, a float in the re-

ceptacle, and an arm connecting the float with the valve, the engagement of the upper portion of the elongated valve with the receptacle preventing the passage from rocking out of registration with the duct by a motion at right angles to that imparted by the float, in the normal operation of the valve, and enabling the arm to be connected to the valve far enough from the seat to reduce the rocking movement of the valve to what is needed to make the valve self-grinding,

the receptacle having a depending lug disposed above the valve, the lug being spaced from the valve and being independent of the valve in the normal operation of the valve to govern the flow of liquid from the inlet to the outlet, the lug constituting a stop for the valve, under an abnormal lift, and then returning it to its normal working position. 5
